(57) **ABSTRACT**

A user worn attachment device for engaging handle straps of bags to allow for hands free carrying of the bags includes a vest, which can be donned by a user. A plurality of hooks is attached to the vest, with each hook being selectively attachable to one or more handle straps of a bag. The bag and its contents thus are attached to the vest and carriable by the user without using their hands.

BACKGROUND OF THE INVENTION

(1) Field of the Invention

The disclosure relates to attachment devices and more particularly pertains to a new attachment device for engaging handle straps of bags to allow for hands free carrying of the bags. The present invention discloses an attachment device comprising a vest to which a plurality of hooks is attached, wherein bags are attachable to the hooks by means of the handle straps.

(2) Description of Related Art Including
Information Disclosed Under 37 CFR 1.97 and
1.98

The prior art relates to attachment devices, which may comprise straps with hooks attached to their opposed ends, clips for attaching bags to user worn belts, and straps attached to hook shaped support arms. What is lacking in the prior art is an attachment device comprising a vest to which a plurality of hooks is attached.

BRIEF SUMMARY OF THE INVENTION

An embodiment of the disclosure meets the needs presented above by generally comprising a vest, which is configured to be donned by a user. A plurality of hooks is attached to the vest, with each hook being configured to attach to one or more handle straps of a bag. The bag and its contents thus are attached to the vest and carriable by the user without using their hands.

There has thus been outlined, rather broadly, the more important features of the disclosure in order that the detailed description thereof that follows may be better understood, and in order that the present contribution to the art may be

2

better appreciated. There are additional features of the disclosure that will be described hereinafter and which will form the subject matter of the claims appended hereto.

The objects of the disclosure, along with the various features of novelty which characterize the disclosure, are pointed out with particularity in the claims annexed to and forming a part of this disclosure.

BRIEF DESCRIPTION OF SEVERAL VIEWS OF
THE DRAWING(S)

10

The disclosure will be better understood and objects other than those set forth above will become apparent when consideration is given to the following detailed description thereof. Such description makes reference to the annexed drawings wherein:

FIG. 1 is an isometric perspective view of a user worn attachment device according to an embodiment of the disclosure.

20 FIG. 2 is an isometric perspective view of an embodiment of the disclosure.

FIG. 3 is a front view of an embodiment of the disclosure.

FIG. 4 is a side view of an embodiment of the disclosure.

FIG. 5 is a rear view of an embodiment of the disclosure.

25 FIG. 6 is an in-use view of an embodiment of the disclosure.

FIG. 7 is a flow diagram for a method utilizing an embodiment of the disclosure.

30 DETAILED DESCRIPTION OF THE
INVENTION

With reference now to the drawings, and in particular to FIGS. 1 through 7 thereof, a new attachment device 35 embodying the principles and concepts of an embodiment of the disclosure and generally designated by the reference numeral 10 will be described.

As best illustrated in FIGS. 1 through 7, the user worn attachment device 10 generally comprises a vest 12, which 40 is configured to be donned by a user. In many respects, the vest 12 resembles a fishing jacket. The present invention anticipates the vest 12 comprising water impermeable material. A slit 14 is positioned in a front portion 16 of the vest 12 and extends from a waistline 18 to a neckline 20 of the vest 12. A closure 22 is attached to the vest 12 and extends along the slit 14. The closure 22, which may comprise a zipper 24, as shown in FIG. 2, buttons, hook 26 and loop fasteners, or the like, is positioned to selectively close the slit 14.

50 A plurality of hooks 26 is attached to the vest 12, with each hook 26 being configured to attach to one or more handle straps 28 of a bag 30. The bag 30 and its contents 32 thus are attached to the vest 12 and carriable by the user without using their hands. The present invention is anticipated to be useful in hands free carrying of any type of bag 30 having handle straps 28, such as, but not limited to, t-shirt bags, corded handle bags, and the like. The hooks 26 of the user worn attachment device 10 also could be used for attachment of other items to the vest 12.

60 A harness 34 is attached to the vest 12 and is configured to distribute a mass of the contents 32 in the bags 30 across a torso of the user. As shown in FIGS. 3 and 5, the harness 34 is attached to an inner surface 36 of the vest 12, although the present invention also anticipates the harness 34 being attached to an outer surface 38 of the vest 12.

The harness 34 comprises a pad 40, a waist strap 42, and a pair of shoulder straps 44. The pad 40 is attached to a rear

portion 46 of the vest 12, proximate to the waistline 18, and is configured to support a back of the user. The waist strap 42 extends from the pad 40 around the waistline 18. Each shoulder strap 44 extends from the pad 40 over a respective shoulder portion 48 of the vest 12 and along the front portion 16 to the waistline 18. As shown in FIGS. 1 and 2, the plurality of hooks 26 comprises four hooks 26 that are attached to the waist strap 42 positioned two apiece on opposed sides 50 of the vest 12 so that the hooks 26 are positioned over a respective hip of the user. The plurality of hooks 26 also comprises two hooks 26 that are attached singly to the shoulder straps 44 so that each hook 26 is positioned over a front of a respective shoulder of the user. The present invention also anticipates other configurations of hooks 26, such as hooks 26 attached to the waist strap 42 along the front portion 16 of the vest 12 and hooks 26 attached to the shoulder straps 44 close to the pad 40.

The user worn attachment device 10 also may comprise a plurality of panels 52. Each panel 52 has opposed edges 54 and a bottom edge 56 that attached to the vest 12 so that the panel 52 defines a pocket 58, which is configured to stow an article, such as a phone, keys, wallet, or the like. Each flap 60 of a plurality of flaps 60 is attached to the vest 12 proximate to a top edge 62 of a respective panel 52 so that the flap 60 is positioned to selectively close an associated pocket 58. As shown in FIG. 3, two panels 52 are attached to the front portion 16 of the vest 12 and define two pockets 58 proximate to the waistline 18 of the vest 12. Other configurations of pockets 58 are anticipated by the present invention.

In use, the user worn attachment device 10 enables a method for hands free carrying of bags 64. The method 64 comprises a first step 66 of providing a user worn attachment device 10 according to the specification above. A second step 68 of the method 64 is donning the vest 12. A third step 70 of the method 64 is attaching one or more bags 30 to the hooks 26 using the handle straps 28 of the bags 30.

With respect to the above description then, it is to be realized that the optimum dimensional relationships for the parts of an embodiment enabled by the disclosure, to include variations in size, materials, shape, form, function and manner of operation, assembly and use, are deemed readily apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A user worn attachment device; a vest configured to be donned by a user; a plurality of hooks attached to the vest, wherein each hook is configured for attaching to one or more handle

straps of a bag, such that the bag and its contents are attached to the vest and carriable without using hands of the user;

a harness attached to the vest, wherein the harness is configured for distributing a mass of the contents in the bags across a torso of the user, wherein the harness comprises:

a pad attached to a rear portion of the vest proximate to the waistline, wherein the pad is configured for supporting a back of the user;

a waist strap extending from the pad around the waistline; and

a pair of shoulder straps, each shoulder strap extending from the pad over a respective shoulder portion of the vest and along the front portion to the waistline; wherein the plurality of hooks comprises two hooks attached singly to the shoulder straps, such that each hook is positioned over a front of a respective shoulder of the user; and

a plurality of panels, each panel having opposed edges and a bottom edge attached to the vest, such that each panel defines a respective pocket, wherein each pocket is configured for stowing an article.

2. The user worn attachment device of claim 1, further including:

a slit positioned in a front portion of the vest and extending from a waistline to a neckline of the vest; and a closure attached to the vest and extending along the slit, such that the closure is positioned for selectively closing the slit.

3. The user worn attachment device of claim 2, wherein the closure comprises a zipper.

4. The user worn attachment device of claim 1, wherein the harness is attached to an inner surface of the vest.

5. The user worn attachment device of claim 1, wherein the plurality of hooks comprises four hooks attached to the waist strap and positioned two apiece on opposed sides of the vest, such that two hooks are positioned over each hip of the user.

6. The user worn attachment device of claim 1, further including a plurality of flaps, each flap being attached to the vest proximate to a top edge of a respective panel, such that each flap is positioned for selectively closing the respective pocket.

7. A user worn attachment device:
a vest configured to be donned by a user;
a slit positioned in a front portion of the vest and extending from a waistline to a neckline of the vest;
a closure attached to the vest and extending along the slit, such that the closure is positioned for selectively closing the slit, the closure comprising a zipper;

a plurality of hooks attached to the vest, wherein each hook is configured for attaching to one or more handle straps of a bag, such that the bag and its contents are attached to the vest and carriable without using hands of the user;

a harness attached to the vest, wherein the harness is configured for distributing a mass of the contents in the bags across a torso of the user, the harness being attached to an inner surface of the vest, the harness comprising:

a pad attached to a rear portion of the vest proximate to the waistline, wherein the pad is configured for supporting a back of the user;

a waist strap extending from the pad around the waistline, the plurality of hooks comprising four hooks attached to the waist strap and positioned two apiece

on opposed sides of the vest, such that two hooks are positioned over each hip of the user, and a pair of shoulder straps, each shoulder strap extending from the pad over a respective shoulder portion of the vest and along the front portion to the waistline, 5 the plurality of hooks comprising two hooks attached singly to the shoulder straps, such that each hook is positioned over a front of a respective shoulder of the user;

a plurality of panels, each panel having opposed edges 10 and a bottom edge attached to the vest, such that each panel defines a respective pocket, wherein each pocket is configured for stowing an article; and

a plurality of flaps, each flap being attached to the vest proximate to a top edge of a respective panel, such that 15 each flap is positioned for selectively closing the respective pocket.
